near Berlin, Germany

Application August 24, 1937, Serial No. 160,677
In Germany September 7, 1936

4 Claims. (Cl. 250—174)

This invention relates to an electron multiplier in which high efficiency is to be obtained by simple means.

Electron multipliers are known in which two rows of plane electrodes are placed opposite each other and in which each electrode has a higher potential than the preceding neighboring electrode. One of the disadvantages of this arrangement is that lines of force of the preceding stage 10 end and lines of force of the following stage begin on the same electrode. That means that secondary electrons liberated from the electrode do not always find an accelerating field which guides them to the next stage. Arrangements are also known in which a magnetic field is provided to 15 guide the electrons so that the electron path between two electrodes has the shape of a half circle. In this case only one row of electrodes is used for production of secondary electrons, 20 whereas the opposite row merely serves for acceleration.

In order to guide the primary electrons to the following electrode without using a magnetic field, and to secure an accelerating field for the 25 secondary electrons liberated at that electrode, it is possible to provide an electron-permeable intermediate electrode, for instance a grid which may be held at about the same potential as the following emitting electrode, so that the fields of subsequent stages no longer contact each other. The 30 accelerating field of the following stage can then cover the entire area of the emitting electrode so that the secondary electrons are surely drawn away. This invention is based on recognition of the 35 fact that a corresponding guidance of the electrons is also possible without employing a grid or similar structure in the path of the electrons. According to the invention this is realized by disposing one or several auxiliary electrodes between 40 two emitting electrodes to one side of the electron path. These auxiliary electrodes are designed in such a manner and held at such a potential that the electrons possess a potential corresponding to that of the more positive of the two electrodes even before impacting the latter. In an especially 45 simple arrangement an emitting electrode of the following stage takes the place of such an auxiliary electrode so that the desired field of distribution is obtained merely by favorable arrangement of these electrodes.

Referring to the drawings, Fig. 1 shows a diagram for the explanation of the effect of the auxiliary electrodes, whereas Figs. 2 to 5 show several embodiments of the invention.

In Fig. 1, the cathode 1 may be photosensitive. An emitting electrode 2 is held at a potential 400 volts higher. The secondary electrons liberated from electrode 2 are accelerated towards the anode 5 and collected by the latter. The anode 50 5 carries a potential of 800 volts. The arrange-

ment may, for instance, be a figure of rotation symmetrical to the axis so that the electrode 2 has the shape of a cone and the anode 5 that of a ring. In this case a ring-shaped auxiliary electrode 3 according to the invention is held at a potential of 600 volts. A potential saddle of about 500 volts is then obtained between the ring 3 and the emitting electrode 2. This causes the electrons coming from the cathode to travel impacting the electrode 2 through a range in which they possess a velocity higher than 400 volts. Immediately in front of this electrode a slight deceleration takes place which, however, is not harmful because the electrons still impact with a velocity sufficient for a secondary-emission ratio greater than unity. The advantage of this arrangement 10 is that an accelerating field is provided for the secondary electrons over the entire area of the emitting electrode 2. This figure shows equi-potential lines according to the potentials 100, 200, 300 volts, and so forth. Some electron paths 15 are schematically indicated.

Fig. 2 shows a multistage amplifier in which emitting electrodes 4, 8, 12, 16, 20 and 24 are held at positive potentials of 400, 800, 1200, 1600 20 volts, and so forth, respectively, with respect to the cathode 0. The emitting electrodes consist of plane plates perpendicular to the plane of the drawing. An auxiliary electrode 6, 10, 14, 18, 22, 26, respectively, is placed before each emitting 25 electrode, and is held at a potential of 600, 1000, 1400, 1800 volts, and so forth, respectively. The auxiliary electrodes may have the shape of pins or wires. The potential distribution shown is then obtained, whereby 200, 400, and so forth, indicate the potentials of the corresponding equi-potential lines. As may be seen from the drawing, a forking of the potential is obtained this 30 time in place of a potential saddle. The emitting electrode 4 is at the same potential as the forked 35 line 400. The electrons coming from the cathode thus possess the full velocity even before trespassing the forked line, in which they impact the electrode 4. The space between both contains a 40 comparatively weak accelerating field leading to the next stage, which however has no considerable influence upon the electrons because of their high velocity. The potential distribution is 45 practically the same as if a grid were disposed in the place of the potential line 400. However, the 50 advantage exists that the electron losses caused by the grid are eliminated and that the construction is more simple.

For further simplification, the auxiliary electrodes are preferably placed somewhat to one 55 side of the row of the emitting electrodes and provided with a higher potential so that they may be held at the same potential as an emitting electrode of a higher stage and may be connected with the latter. This case is shown in Fig. 3, and 60

is principally the same arrangement, however, but with cylindrical emitting electrodes. The cathode 0 and the emitting electrodes 8 and 16 surround the emitting electrodes 4 and 12, which are positioned in the interior. The auxiliary electrodes 8', 12', 16', and 20' have the shape of concentric rings and are each connected with one of the other electrodes. The plate 20 serves as a collector. The potentials of the electrodes are indicated by the reference numbers the same as already in Fig. 2. Light is projected through a lens 31 upon a concentrically arranged cone-shaped mirror 32, which uniformly distributes it upon the cathode 0.

15 Fig. 4 shows a cross-section of a further modification of the embodiment according to Fig. 2. The reference numbers completely correspond to those of Fig. 3. However, the electrodes are substantially plane and have the shape of flat, concentric rings with diameters increasing from stage to stage. The arrangement is a figure of rotation around the axis AA. The electrodes 4 and 8 have a slight curvature at the edge facing the anode 20. Hereby the field of the electrodes 25 16' and 20', which are held at a high potential, is screened off. In this manner electrons are headed for the emitting electrode under a nearly grazing angle which would otherwise probably pass the electrode without impacting.

30 Fig. 5 shows an arrangement in which no auxiliary electrodes are necessary but in which the desired potential distribution is obtained merely by suitable design and arrangement of the electrodes. The potentials are again indicated by 35 the reference numbers, the cathode by 0, the emitting electrodes by 4 and 8, and the collectors by 12. The electrodes may be formed as columns perpendicular to the plane of the drawing with the exception of the electrodes 0 and 4, or also 40 as rings placed above and below the plane of the drawing. In the first case the cathode may, for instance, be a thermionic cathode which emits only in the direction of the electrode 4. Equi-potential lines in steps of 100 volts are shown, 45 from the shape of which it may be seen that a saddle of about 500 volts is obtained in front of the electrode 4, and a saddle of about 900 volts is obtained in front of the electrodes 8. Thus, an accelerating field is provided over the entire area 50 of the emitting electrode, which draws away the secondary electrons and guides them to the following electrode where they impact under an angle of about 90 degrees.

The arrangements of Figs. 1 and 5 may also 55 be modified by moving the electrodes 2, or 4 and 8, respectively, in the direction of the source of electrons, so that they lie exactly in the potential saddle. The shapes of these electrodes are then made corresponding to the equi-potential surfaces labeled 500 and 900 volts, respectively, and are held at these potentials. In order to guide possibly all emitted electrons to the next higher stage the electrode may have a concave curvature at the emitting area so that a lens effect 60 occurs. This is shown in the shape of the electrode 1, in Fig. 1.

If a carrier frequency is to be introduced, a high-frequency potential is applied to one of the electrodes. The application of the high frequency to one or several of the auxiliary electrodes has the advantage that all emitting electrodes may be connected to ground by condensers. This is highly desirable for elimination of interference, so that the interference is

not carried through further stages and amplified. An amplification of any stray electrons impacting the auxiliary electrodes is impossible.

It may be understood that the potentials indicated in the drawings are only examples. All 5 electrode arrangements are incorporated in a vacuum receptacle in a suitable manner. The electron multiplier according to the invention may also be combined with another device, for instance a picture analyzing tube with stationary 10 scanning aperture, and incorporated in the same vacuum space.

Having thus described my invention, I claim:

1. An electron multiplier comprising a source 15 of electrons, a secondary electron emissive electrode in electron collecting position with respect to said cathode and capable when at a positive potential with respect to said source of normally accelerating an electron from said source to said electrode to reach a velocity of impact at said 20 electrode equal to the potential thereof, and another electrode of substantially less exposed surface area than said first electrode, located in a plane intermediate said cathode and said first electrode but out of the path of travel of said 25 electron, for increasing the rate of acceleration of said electron to thereby cause it to reach its impact velocity prior to impacting said first-mentioned electrode.

2. An electron multiplier comprising a source 30 of electrons, a secondary-electron emissive electrode in electron collecting position with respect to said source of electrons and capable when at a positive potential with respect to said source of normally accelerating an electron from said 35 source to said electrode to reach a velocity of impact at said electrode equal to the potential thereof, and another electrode in a plane intermediate said cathode and said first electrode symmetrically disposed with respect to said first electrode and located out of the path of travel of said electron, for increasing the rate of acceleration of said electron to thereby cause it to reach its impact velocity prior to impacting said first-mentioned electrode.

3. An electron multiplier comprising a source of electrons, a secondary-electron emissive electrode in electron-collecting position with respect to said cathode, and another electrode located in a plane intermediate said source and said secondary-emissive electrode but outside the path of travel of an electron from said source to said secondary-emissive electrode and electrode means for withdrawing electrons from said secondary-emissive electrode without substantial interference with electron-guiding fields created by said prior-recited electrodes, after energization thereof.

4. An electron multiplier comprising a source of electrons, a secondary-electron emissive electrode in electron-collecting position with respect to said cathode and capable when at a positive potential with respect to said source, of normally accelerating an electron from said source to said electrode to reach a velocity of impact at said 60 electrode equal to the potential thereof, and electrode field-producing means in a plane intermediate said cathode and said first electrode but out of the path of travel of electrons from said cathode, and means for withdrawing secondary 65 electrons from said secondary-emissive electrode without substantial interference with the fields produced by said prior-recited electrodes.

ROLF COLBERG.
